[57] CLAIM

The ornamental design for a telephone book, as shown and described.

DESCRIPTION

FIG. 1 is a top perspective view of a telephone book, showing my new design;

FIG. 2 is a top plan view of an inside page thereof;

FIG. 3 is a top plan view of a second inside page thereof;

FIG. 4 is a top plan view of a third inside page thereof;

FIG. 5 is a top plan view of a fourth inside page thereof;

FIG. 6 is a rear elevational view thereof; and

FIG. 7 is a left side elevational view thereof.

The bottom plan views opposite FIGS. 1-5 are flat and unornamented.

The broken lines indicating indicia in FIGS. 1 and 3-5 are shown for illustrative purposes only.

FIG. 2

FIG. 1

FIG. 3

FIG. 4

FIG. 5

FIG. 6

FIG. 7
